To all whom it may concern:

Be it known that I, Jean Perinet, a citizen of France, residing at 45 avenue de l'Opera, Paris, France, have invented a new, original, and ornamental Design for a Perfume Bottle, of which the following is a specification, reference being had to the accompanying drawing, forming a part hereof.

Fig. 1 is a front elevational view of a perfume bottle, showing my new design;

Fig. 2 is a side elevational view thereof;

Fig. 3 is a rear elevational view thereof; and
Fig. 4 is a perspective view thereof showing the stopper portion removed from the bottle.

I claim:

The ornamental design for a perfume bottle, as shown.
